Primary Examiner—Mimosa De**CLAIM**

The ornamental design for a reclining chair, substantially as shown and described.

DESCRIPTION

FIG. 1 is an upper left front perspective view of a reclining chair in an upright position of my new design;

FIG. 2 is a front elevational view of the reclining chair in FIG. 1;

FIG. 3 is a right side elevational view of the reclining chair in FIG. 1, the left side is a mirror image thereof;

FIG. 4 is a rear elevational view of the reclining chair in FIG. 1;

FIG. 5 is a top plan view of the reclining chair in FIG. 1; FIG. 6 is a bottom plan view of the reclining chair in FIG. 1;

FIG. 7 is an upper left front perspective view of the reclining chair in a first reclined position;

FIG. 8 is a front elevational view of the reclining chair in FIG. 7;

FIG. 9 is a right side elevational view of the reclining chair in FIG. 7, the left side is a mirror image thereof;

FIG. 10 is a rear elevational view of the reclining chair in FIG. 7;

FIG. 11 is a top plan view of the reclining chair in FIG. 7; FIG. 12 is a bottom plan view of the reclining chair in FIG. 7; and,

FIG. 13 is a right side elevational view of the reclining chair in a second reclined position.

The broken lines showing the reclined hardware in FIGS. 2, 6, 7-9, and 11-13 are for illustrative purposes only and form no part of the claimed design.
